UNITED STATES PATENT OFFICE.

LLOYD C. CRIPPEN, OF PARSONS, AND CHRISTIAN H. SCHLINKMEIER, OF WALNUT,
KANSAS.

LIFTING-JACK.

1,330,306.

Specification of Letters Patent. Patented Feb. 10, 1920.

Application filed April 26, 1919. Serial No. 292,892.

To all whom it may concern:

Be it known that we, LLOYD C. CRIPPEN and CHRISTIAN H. SCHLINKMEIER, citizens of the United States, residing at Parsons 5 and Walnut, in the counties of Labette and Crawford and State of Kansas, have invented certain new and useful Improvements in Lifting-Jacks, of which the following is a specification.

10 The invention provides a jack designed chiefly for use in connection with vehicles for lifting the wheels from the ground to admit of removal of the wheel for lubricating or other purpose or to admit of repairing 15 or replacing a tire.

The invention provides a vehicle jack which is quick acting and which may be reduced to compact form for convenience of carrying on the vehicle so as not to be in 20 the way or occupy valuable space.

25 The drawing illustrates a preferred embodiment of the invention. However, it is to be understood that in adapting the same to meet different conditions, various changes in the form, proportion, and minor details 30 of construction may be resorted to without departing from the nature of the invention as claimed hereinafter.

Referring to the drawing, 35 Figure 1 is a side view of a vehicle jack embodying the invention as it appears when in service.

Fig. 2 is a top view.

Fig. 3 is a front view.

40 Fig. 4 is a detail view showing more clearly the manner of connecting the several parts.

Corresponding and like parts are referred to in the following description and indicated in the several views of the drawing by like reference characters.

45 The jack comprises essentially three parts, a standard A, a lifting beam B and an operating lever C. The standard A is approximately of A shape and consists of a single bar of metal bent into the form substantially, as indicated in Fig. 3. A cross bar *a* connects the side members of the standard near their lower ends and besides forming 50 a brace constitutes a stop to limit the movement of the lever C in one direction. The cross bar *a* has its end portions bent to engage the inner faces of the side members of the standard to which they are secured by rivets or other suitable fastening means.

The operating lever C is mounted upon a pin 1 and this pin also serves as means for connecting the upper ends of the side members of the standard A. The short arm of the lever C is provided with an open slot 60 or notch 2 which is adapted to receive a pin 3 at the movable end of the lifting beam B. The long arm of the lever C is of a length so that its lower end will engage the cross bar *a* and thereby limit the movement of 65 the lever when its long arm is swung downward into the plane of the standard when the latter is in upright position.

The lifting beam B comprises two sections 4 and 5 which are pivotally connected 70 at 6, whereby to admit of the sections folding one upon the other to reduce the length of the beam. The section 4 consists of a single bar whereas the section 5 comprises companion bars which are spaced apart a 75

distance to receive the section 4 and the end of the lever C. This is indicated most clearly in Fig. 2. When the sections 4 and 5 are extended and aline they are retained in the position indicated by means of the pin 6 and an element 7, the latter consisting of a metal strap extending over the upper edges of the companion bar and having their end portions bent to engage the outer faces of the bars to which they are attached 80 by suitable fastening means. When the section 4 is extended it engages the part of the strap extending across the space formed between the companion bars comprising the section 5.

When the lifting beam is reduced 90 in length the section 4 is folded so as to occupy the space formed between the companion bars constituting the section 5. The pin 3 connecting the opposite ends of the companion bars receives the notch or slotted end of the lever C. A plurality of stops 8 is provided along the upper edges of the bars comprising the section 5 to engage the axle or other part to be lifted. 95

When the jack is reduced to compact form 100 the lifting beam is disengaged from the operating lever C and the section 4 is folded between the companion bars of the section 5. The lever C is folded to occupy a position in the plane of the standard. The folded lifting beam may be placed against the standard, thereby occupying a small space. When the jack is set up for use the section 4 is extended and the lever C is adjusted to receive the pin or like fas- 110

tening 3 in the notch or slot 2. The standard is placed in upright position and the lower end of the lifting beam is engaged with the ground or other surface. The free end of the lever C is swung upwardly, thereby lowering the upper portion of the lifting beam. The jack is adjusted so that the axle or part to be lifted engages the lifting beam adjacent one of the stops 8 after which the long arm of the lever C is swung downwardly against the cross bar a with the result that the upper portion of the lifting beam is elevated and lifts the part resting thereon.

The foregoing description and the drawing have reference to what may be considered the preferred, or approved form of our invention. It is to be understood that we may make such changes in construction and arrangement and combination of parts, materials, dimensions, et cetera, as may prove expedient and fall within the scope of the appended claim.

Having thus fully described our invention, what we claim as new and desire to secure by Letters Patent is:—

A lifting jack, comprising a standard, an operating lever pivoted thereto and having one end formed with a notch or open slot, a lifting beam comprising two sections, one of the sections comprising spaced companion bars, a fastening connecting the bars at one end and adapted to enter the notch or open slot of the operating lever, a connecting element joining the opposite ends of the bars and a fastening pivotally connecting the other section with the bars of the first mentioned section, the parts being adapted to fold into compact form.

In testimony whereof we affix our signatures in presence of two witnesses.

LLOYD C. CRIPPEN.
CHRISTIAN H. SCHLINKMEIER.
